[57] ABSTRACT

A cutting rotor of the general type commonly used in wood working planers and jointers has blades secured in slots in a hub by clamping screws that at least partially intersect the blades, and also generate a clamping pressure on the side of the blade nearest the axis of rotation of the rotor. The center of gravity of the screws is disposed with respect to the axis of rotation so that movement of the screws induced by running vibrations and centrifugal force will tend to increase the clamping pressure. The screws are accessible for adjustment on the exterior of the assembly via openings in the hub and blades.

CUTTING ROTOR ASSEMBLY

BACKGROUND OF THE INVENTION

The cutting action of planers and jointers commonly used in wood working operations is based upon a rotor assembly which includes a generally cylindrical hub having slots extending parallel to the axis of rotation, and disposed tangentially with respect to a cylinder somewhat less in diameter than that of the cylindrical periphery of the hub. The blades extend to sharpened edges projecting from the hub periphery, and these blades are normally clamped securely in position such that all of the blades operate on the same circumscribed cylindrical surface.

These rotor assemblies rotate at very high speed, and it is obvious that the clamping of the blades in position is vital both to the proper operation of the machine, and to assure the safety of the operator. The clamping action must be secure enough to resist the action of centrifugal force, running vibrations, and the shock forces inevitably resulting from contact of the blade with hard portions of the wood, or foreign material that may be embedded in it. With regard to the action of centrifugal force, it should be noted that the position of the center of gravity of the blades within the slots is such that centrifugal force will establish a very strong tendency for the blades to move toward emergence from the slots. Previous systems for securing a blade in position have included clamping screws in threaded engagement with the portion of the hub radially outward from the blade slots, and which generate an inward clamping pressure against the blades. The arrangements also include some rather complex wedging systems, in which the blade slots are of a width considerably greater than that of the blade, and taper to an increased width toward the central portion of the hub. Wedge assemblies bearing against the radially inner face of the blades are set firmly in position, and any tendency for the blades to move outward from the slots will correspondingly tend to drag the wedge units into tighter clamping because of the convergence of the blade slots. These wedge units have occasionally included blocks bearing against one wall of the blade slots, together with screws in threaded engagement with the blocks, with the heads of these screws bearing directly against the inner face of the blades. Adjustment of the blades to the proper cutting position is difficult in both types of locking, and any looseness of any of this clamping equipment produces an extreme danger, as well as improper cutting action. It is the primary purpose of the present invention to provide a locking system of the blades which is readily adjustable and will maintain the safety of the machine even under improper adjustment of the clamping system.

SUMMARY OF THE INVENTION

The hub of a rotor embodying the present invention is provided with slots of a width slightly in excess of blade thickness, and arranged tangentially with respect to a cylinder of less diameter than that of the cylindrical periphery of the hub. These slots can be traversed by locking screws that have a head portion of a diameter adapted to closely interengage with openings in the blades. This portion extends from the end of the screw to a shoulder which has a diameter larger than that of the blade opening. A bore of sufficient diameter to receive the shoulder portion of the screw extends from

the periphery of the rotor on an axis preferably perpendicular to the blade slot to a position such that the screw can be run inward to the point where its head will completely clear the blade slot. This bore obviously intersects the blade slot. Extending inward from this bore is a coaxial threaded bore which is in threaded engagement with the screw.

Blades are inserted into the slots with the screws run into a position in which they do not obstruct the slots. 10 When the blades are in position, the screws are back-rotated to the point that the end extremities of the screws become interengaged with the openings in the blades. At this point, prior to the further tightening of the screws, the blades are securely interlocked with the hub so that they cannot be thrown out. In one form of the invention, openings in the blades are circular, and fit closely with the intersecting head portions of the screws so that the screws function as a locating system for automatic placement of the blades in cutting position. 15 In another form of the invention, the openings in the blades are elongated to permit adjustment of the blades to greater or less extension from the blade slot. This adjustment is made through access openings intersecting the inner extremities of the slot, so that the screw driver can be inserted at this point and bear on the inner edge of the blades to extend it as desired by rotation of the screw driver. The locking screws are preferably of a form similar to that associated with the so-called "Allen" recessed-head cap screws. This arrangement is preferable to the use of a screw driver slot, as the operating tool is kept out of contact with the opening in the blade, and thus preserves the close fit preferable at this point.

DESCRIPTION OF THE DRAWINGS

FIG. 1 is a perspective elevation of a machine adapted for placement in a position for carrying and driving a small jointer.

FIG. 2 is a view of an enlarged scale over that of FIG. 1, illustrating the placement of a small jointer on the table of the machine shown in FIG. 1, with that machine swung to a position in which the column is horizontal.

FIG. 3 is a side elevation on an enlarged scale of the rotor assembly used in the machine illustrated in FIG. 2.

FIG. 4 is a plan view of an adjustable blade useable in conjunction with the assembly.

FIG. 5 is a plan view of a fixed-position blade useable with the rotor assembly.

FIG. 6 is an elevation showing the locking screw.

FIG. 7 is a section on an enlarged scale on a plane normal to the axis of rotation of the rotor at the locking screws.

FIG. 8 is a section on an enlarged scale of the rotor on a plane normal to the axis of rotation, taken at one of the adjustment axis openings.

FIG. 9 is a section similar to FIG. 7, but showing the blades and locking system as they are being installed or removed from the hub.

DESCRIPTION OF THE PREFERRED EMBODIMENTS

The small jointer indicated generally at 10 in FIG. 2 is designed to be mounted on and driven by the machine illustrated in FIG. 1. This machine has the base 11 supporting a fixed column 12 having a pivot mem-

ber 13 secured to its upper extremity. This member rotatably supports a shaft assembly 14 fixed with respect to the clamp 15 embracing the moveable column 16 carrying the powerhead 17. This powerhead can be identical to that of a standard light-duty drill press. A table 18 has an extension at 19 at the rear of its underside, and the table unit is adjustably secured to the bracket 20 for movement about an axis perpendicular to that of the column 16. A clamping bolt 21 constricts the bracket about the column 16 to secure the table assembly in position, and a similar clamping bolt 22 constricts the clamp 15 about the column 16 to hold the position of the powerhead and the column with respect to the base assembly.

The jointer 10 shown in FIG. 2 is supported on the table 18, with the machine shown in FIG. 1 placed in a position in which the column 16 is horizontal by rotation about the axis of the shaft assembly 14. In this position, a short shaft (not shown) is carried by the chuck 23 of the powerhead, and the sheave 24 is carried on this shaft to drive a jointer sheave 25 with the belt 26. Tightening and loosening of the belt 26 is accomplished by relative angular displacement of the bracket 20 with respect to the powerhead 17 about the axis of the column 16.

The jointer sheave 25 is carried by the shaft 27, which is an extension of the hub 28 of the cutting rotor. This rotor operates in a recess intersected by the planes of the table sections 29 and 30, which receive the work pieces. As viewed in FIG. 2, these pieces are placed on the surface 29, and moved to the left across the surface 30. Normally, the surface 30 will be slightly above the level of the surface 29 by an amount substantially equal to the thickness of the cut being taken by the machine. The guard 31 pivots in a horizontal plane about the axis of the pin 32 as the workpiece moves across the area occupied by the rotor. A fence 33 provides a lateral positioning stop, and also establishes a 90° orientation with respect to the surfaces 29 and 30. As thus far described, the jointer 10 is of conventional construction.

The rotor assembly shown in FIG. 3 is supported at the right end by a bearing (not shown) fixed with respect to the base 34 of the jointer 10, and at the left end by the removable bearing block 35 attached normally to the base 34. The bearing block receives the shaft extension 27, with the fixed bearing in the frame supporting the short journal 36.

A group of three removable blades is secured to the hub 28 by three clamping screws of the type shown in FIG. 6 for each blade. In the illustrated modification, three blades are installed in the rotor at three equally angularly spaced positions about the axis of the shaft sections 27 and 36. The system for securing each of the three blades is identical, and only one of these will be described in detail. Referring to FIG. 8, the rotor 28 is provided with slots 37 parallel to the axis of rotation of the rotor, and it is preferable to provide a cut-away area as indicated at 38 ahead of each blade slot, with respect to the direction of rotation of the rotor, to provide chip clearance. The width of the slot 37 is preferably a few thousandths of an inch greater than the thickness of the blades 39, with the end of the slot being defined by the surface 40. Holes 41 and 42 intersect the slot 37 at a point opposite the surface 40 to provide access to the back edge of the blades 39 for purposes of adjustment. A screw driver can be inserted in the holes

41 and 42, and rotated to generate a force between the blades and the hub to project blades to a larger diameter.

Referring to FIG. 9, the insertion of the blades into position in the hub is accomplished by running the screws 43 into a position such that they do not obstruct the slots 37. These screws are each received in bores 44 a-c, which are very slightly larger in diameter than the diameter of the shoulder 45 of the screws. These bores 10 intersect the slots 37, and extend far enough beyond the slots so that the entirety of the heads of the bolts 43 can be placed beyond a position obstructing the slots. The threaded portions 46 of the screws 43 are in threaded engagement with the hub 28 at 44d, and the 15 screws are manipulated preferably through interengagement of a conventional Allen wrench interengaged with the hexagonal recess 47 of the screws. The blades 39 have elongated holes 48-50 slightly larger in width than the diameter of the cylindrical end portion 51 of 20 the screws 43. The diameter of the shoulder 45 is considerably greater than the width of the elongated holes 48-50. With the blades 39 inserted in the relationship shown in FIG. 9, a blade position is finally reached in 25 which the screws 43 become accessible through the holes 48-50 in the blades, and the screws may then be back-rotated to the point that the end portions 51 intersect the holes 48-50. It is obvious that the blades are now locked to the hub, even prior to the generation of any clamping action.

30 The degree of extension of the blades 39 so that cutting edges 52 operate on the desired circumscribed cylindrical surface is now accomplished by a combination of pushing the blades inwardly, and extending them by manipulation through the access openings 41 and 42.

35 When the blades have been placed in their proper position, further back-rotation of the screws 43 will establish a clamping action against the underside of the blades (with respect to the axis of rotation) which can be sufficiently intense to assure the maintenance of the 40 adjusted position of the blades. The insertion and final adjustment of the blades will normally be done one at a time, and the completion of this procedure produces the relationship shown in FIG. 7. In the modification shown in FIG. 5, the blade 53 has cylindrical openings 45 54-56 of a diameter slightly in excess of the diameter 51 of the screws 43. In this modification, the adjustment access openings 41 and 42 would not be necessary, as the blade is oriented completely by interengagement of the screws with the blades. This form of 50 the invention is particularly well adapted to the use of disposable blades, which may be of relatively inexpensive low-carbon steel, supplemented by case-hardening. One or two sharpenings of such inexpensive blades can be provided for, after which the blades are thrown away. The removal of the need for adjustment makes it easy for the user of the jointer 10 to take the blades out himself, and either sharpen or replace them. Where the blade form shown in FIG. 4 is used, it is still 55 possible to make the adjustments with the rotor remaining in operating position in the machine, by placement of a reference bar on the table surface 30, and adjusting the blades to the point where this bar is barely contacted by the cutting edge 52 of the blades 39. This practice is feasible primarily as a result of the fact that 60 all of the clamping action can be generated by the use of the tools positioned in a generally radially direction, with the tools extending out through the operating slot 65

of the machine occupied by the rotor. The extension of the blades from the slots by the insertion of tools in the openings 41 and 42 is also done from a generally radial direction.

I claim:

1. A cutting rotor having a central portion provided with at least one slot, a blade partially received in said slot, and securing means holding said blade in said slot, wherein the improvement comprises:

means on said central portion defining at least one

outer bore intersecting said slot and the surface of said central portion, and a threaded inner bore coaxial with said outer bore; and

screw means constituting said securing means and having a major diameter head portion selected to fit closely with said outer bore, a threaded portion at one side of said major head diameter portion adapted to engage said threaded inner bore, and a minor diameter head portion on the opposite side of said major diameter head portion from said threaded portion, said blade having an opening adapted to receive said minor diameter head portion and obstruct said major diameter head por-

5

10

15

20

tion, said outer bore extending inward beyond said slot by an amount providing for inward movement of said screw means to a position to admit said blade into said slot past said minor diameter head portion, said screw means having a drive recess in the end thereof adjacent said minor diameter head portion.

2. A rotor as defined in claim 1, wherein said blade opening is circular and adapted to fit closely with said minor diameter head portion.

3. A rotor as defined in claim 1, wherein said blade opening is elongated to receive said minor diameter head portion in various positions of extension of said blade from said slot.

4. A rotor as defined in claim 3, additionally including means forming an access aperture intersecting said slot and the surface of said central portion.

5. A rotor as defined in claim 4, wherein said access opening intersects the inner extremity of said slot.

6. A rotor as defined in claim 1, wherein said drive recess is isolated from the periphery of said minor diameter head portion.
